FIG. 2

FIG. 3

INVENTOR:
JOHN S. HOUSMAN
BY: Clarence J. Poole

ATTORNEY

Patented Oct. 4, 1927.

1,644,252

UNITED STATES PATENT OFFICE.

JOHN S. HOUSMAN, OF CHICAGO, ILLINOIS, ASSIGNOR TO GOODMAN MANUFACTURING COMPANY, OF CHICAGO, ILLINOIS, A CORPORATION OF ILLINOIS.

SCRAPER.

Application filed September 30, 1921, Serial No. 504,443. Renewed March 28, 1927.

This invention relates to improvements in scrapers used in transporting loose material, and more particularly to scrapers of the class having reciprocating movement toward and away from the material to be transported, and provided with a rear end portion adapted to be opened during the rearward movement to gather the load, and closed during the forward movement.

10 The object of my invention is to provide means for loosening material and loading the scraper of the class above described. The invention may best be understood by reference to the accompanying drawing, 15 which illustrates the use of my device as applied to one form of open-end scraper which is similar to that disclosed in a co-pending application of Glenn W. Packer, Serial No. 470,771, filed May 19, 1921, now 20 Patent 1,465,456, Aug. 21, 1923, and assigned to assignees of the present application.

In the drawing, Figure 1 is a top plan view of the scraper to which my invention 25 has been applied with parts broken away. Fig. 2 is a longitudinal cross-section of the scraper. Fig. 3 is a view showing the scraper in use in a mine and illustrating the purpose of my invention.

30 This form of scraper illustrated comprises a body portion 12 having side walls 13, 13, connected by front and rear cross members 14 and 15 respectively. The rear end of the scraper is provided with a pair of pivoted wall portions 17, 17, arranged to form a closure, but mounted to swing rearwardly and laterally into substantial alignment with the side walls during the rearward movement of the scraper so as to load the same. The 35 scraper is operated by means of a head rope 10 and a tail rope 11 trained over fixed guides or sheaves and operatively connected to any suitable power device such as a hoisting engine. Means coacting with the draft 40 ropes for actuating the rear wall portions 17, 17, comprises a pair of flexible terminals 10^a, 10^a, connected to the head rope 10, and a pair of flexible terminals 11^a, 11^a, connected to the tail rope 11. The terminals 45 10^a, 10^a, are each trained through a suitable guide 26 adjacent the front end of a side wall 13, and from thence to a supporting member 27 attached to and extending inwardly from each wall portion 17. Suitable stop members 19 and 22 are connected

with a second supporting member 20 extending inwardly from the wall portion 17 above the supporting member 27, said stop members being adapted to engage the cross member 15 to limit the inward movement of 60 its respective wall portion. The outward movement of the walls may be limited by means of a pair of members 22 pivoted on arms 20 and extending through an angle member 22^a secured to the bottom of cross-bar 15. The extreme forward ends of the stop members 22 are bent downwardly to engage the angle bar 22^a when the wall portions 17, 17 are in their extreme outermost positions, as shown in dotted lines in Figure 1. It will now be seen that when the scraper is pulled rearwardly by means of the tail rope 11 the end wall portions 17, 17, swing outwardly into substantial alignment with the side walls 13, 13. The scraper 70 may thus be pulled into a pile of material as illustrated in Fig. 3. When the tail rope is released and the head rope 10 is pulled, the end wall portions 17, 17, are swung inwardly and closed, so that the loose material within the scraper is carried forwardly 75 away from the pile.

Referring now to the features and objects of my present invention, it will be observed that I provide the scraper with means projecting rearwardly above the opening thereof, which means is adapted to engage and loosen the adjacent material so that it will readily be dislodged from the pile and fall into the scraper. In the embodiment of my invention as illustrated, this means comprises a plurality of pick members 30, 30, three in number mounted on the cross members 14 and 15 and extending rearwardly 80 above the wall portions 17, 17, in position to engage the loose material as shown. These pick members are preferably provided with slots 31, 31, having clamping members 32, 32, extending therethrough so as to permit longitudinal adjustment of said members. 90

It is usually desirable that the pick members extend rearwardly beyond the limit of movement of the side walls 17, 17, as shown in Fig. 1, but said pick members may be readily retracted from this position if desired as illustrated in dotted lines in Fig. 1.

The operation of my device is illustrated in Fig. 3, which shows the scraper in digging position at the toe of a pile of loose material indicated at 33. The scraper is 110

pulled into the pile by means of the tail rope 11, with end wall portions 17, 17, in opened position so as to readily enter the pile to obtain its load. The material is loaded into the scraper as the latter is moved rearwardly into the pile, and when the movement is reversed, by pulling on the head rope 10, the end wall portions 17, 17, are closed so as to carry the load forwardly. Sometimes it is not possible to obtain a sufficient load in one rearward movement, and in such case the scraper is moved backward and forward several times to obtain a full load. At all events, as the toe of the pile is diminished, the incline of the face becomes quite steep, and the material is often packed so solidly that it is necessary to dislodge the loose material in order to load the scraper readily. By means of the pick members 30, 30, it will be seen that the material will be dislodged and fall in loose condition so that it may be readily gathered in the scraper.

Under ordinary conditions the scraper maintains its normal relation parallel to the ground as shown in full lines in Fig. 3, but I have noticed that sometimes the scraper is tipped upwardly, somewhat as indicated in dotted lines in this figure. The tipping may be caused either by reason of the arrangement of the tail rope which often is inclined upwardly as shown in Fig. 3, or by reason of the fact that the forwardly extending cutting edges of the end wall portions 17, 17, sometimes meet sufficient resistance at the bottom of the inclined toe of the pile to tip the scraper slightly as shown. I find that when the scraper has a tendency to tip upwardly, as described, the pick members 30, 30, tend to counteract this tendency as they engage the inclined face of the pile serving to stabilize the movement of the scraper while it is being loaded.

Although I have shown and described one form in which my invention may be em-

bodied, it will be understood that many other means may be employed for accomplishing the same results without departing from the spirit and scope of my invention. I do not therefore wish to be understood as limiting myself to the specific construction illustrated herein excepting as specifically limited in the appended claims.

I claim as my invention:

1. In combination with a scraper of the class described, means between the lateral margins and above the body of the scraper, extending in advance thereof, for dislodging loose material.

2. In combination with a reciprocably operated scraper having one end thereof provided with a movable closure adapted to be opened while loading, a pick member fixed to the scraper and projecting longitudinally beyond said closure for dislodging loose material during the loading of the scraper.

3. In combination with a scraper having pivotal end wall portions movable into substantially parallel relation with each other when in open position, means for moving said wall portions, and a plurality of pick members fixed to the scraper and extending above said wall portions, substantially in alignment with the marginal limits of the latter, when in open position.

4. In combination with a scraper having pivotal end wall portions movable into substantially parallel relation with each other when in open position, means for moving said wall portions, a plurality of pick members fixed to the scraper and extending above said wall portions, and means for adjusting said pick members relative to the marginal limits of said movable wall portions when the latter are in open position.

Signed at Chicago, in the county of Cook, and State of Illinois, this 28th day of September, 1921.

JOHN S. HOUSMAN.
